CLAIM

The ornamental design for a speaker bracket, as shown and described.

DESCRIPTION

FIG. 1 is a perspective view of a speaker bracket showing our new design;

FIG. 2 is a top plan view thereof;

FIG. 3 is a bottom plan view thereof;

FIG. 4 is a front or rear elevational view thereof;

FIG. 5 is a right side elevational view thereof; and,

FIG. 6 is a left side elevational view thereof.

The broken line showing of the speaker in FIG. 1 and the openings in FIGS. 1-4 is for illustrative purposes only and forms no part of the claimed design.
